UNITED STATES PATENT OFFICE.

SAMUEL TROOD, OF PITTSBURGH, PENNSYLVANIA.

OVEN.

1,393,650.

Specification of Letters Patent. Patented Oct. 11, 1921.

Application filed September 24, 1920. Serial No. 412,575.

To all whom it may concern:

Be it known that I, SAMUEL TROOD, a citizen of the United States, residing at Pittsburgh, in the county of Allegheny and State of Pennsylvania, have invented a new and useful Improvement in Ovens, of which the following is a full, clear, and exact description.

The present invention relates to ovens, and more especially to ovens of the so-called continuous tunnel type, in which the articles to be heated travel through a long tunnel-like heating chamber.

The object of the invention is to secure a better regulated heat distribution in the oven chamber.

Other features of the invention relate to certain combinations and arrangements of parts hereinafter described and more particularly pointed out, the advantages of which will be apparent to those skilled in the art from the following description.

The present invention is illustrated and described with particular reference to a continuous tunnel oven having two lines of oppositely moving articles traveling through the heating chamber. It is to be understood, however, that the invention is not limited to its illustrated embodiment but may be embodied in other oven structures.

In the drawings, which illustrate the preferred embodiment of the invention, Figure 1 is a horizontal section through the oven;

Fig. 2 is a vertical transverse section through the oven;

Fig. 3 is a detail view of the air preheating pipes;

Fig. 4 is a detail view illustrating a modified construction of the heat shields, and

Figs. 5, 6 and 7 are detail views showing one of the heat flues and its conducting plates and illustrating different ways in which the desired heat zones may be maintained.

As shown in the drawings, the oven 1 is a long structure having a long tunnel-like heating chamber 2. The goods or articles to be heated travel through the oven chamber in two rows traveling in opposite directions. The articles are shown as carried on trucks 3 which move in opposite directions on two sets of tracks 4 and 5. The trucks have metal frames upon which are carried refractory platforms or tables 6 upon which the articles to be heated are placed. The articles to be heated are illustrated as sag-

gers inclosing ceramic ware. These are shown merely for the purpose of illustration, as any desired articles may be heat treated in the oven. The trucks are provided with the usual sand seals 8 to prevent the hot gases from getting beneath the metal bodies of the trucks. The two rows of trucks are pushed through the furnace by means of any suitable mechanism, illustrated, for example, as pushers 9. The ends of the furnace chambers are closed by refractory doors 10. The ends of the furnace have vestibules or antechambers 11 which form air locks for the introduction and withdrawal of the goods from the furnace chamber. These antechambers have doors 12 which are closed when the oven doors 10 are open.

The oven chamber is heated by means of two heating flues 20 on opposite sides of the chamber 2. A burner 21 discharges into the combustion chamber 22 of the heating flue where combustion takes place. The products of combustion travel along the flue proper 23 to the chimney flue 24. An opening 25 is provided for diverting a fraction of the hot gases of combustion from the flue 23 to the mouth of the burner 21 to assist in elevating the temperature of the gases where combustion takes place. It will be noted that the burner 21 discharges into the combustion chamber 22 in one direction, and that the gases turn on themselves and flow along the side of the combustion chamber next the oven and along the flue in the opposite direction. This enables me to get the desired heat concentration at the right places. The air for combustion is preheated in a U-shaped preheating pipe 26 located at the end of the flue 23, the preheated air passing from this preheating pipe along the pipe 27 to the burner. The burner is supplied through a fuel pipe 28 with gas or other fuel.

The outer walls 30 of the furnace are formed of suitable refractory heat-insulating material. The gases of combustion are kept from contacting with the articles to be heated by means of heat-conducting partition walls 31 between the combustion chambers and flues, and the oven chamber. These walls are shown as made of corrugated plates for the purpose of getting more surface to transmit the heat through the partitions. The walls 31 are made of a highly refractory heat-conducting material where

the heat is the strongest. As shown in the drawings, the portion 32 of the partition is made of plates of carborundum. The portion of the wall 33 where there is less heat is shown as made of corrugated metal which conducts heat more readily than the carborundum but which could not be used at the highly heated portion of the flue.

The plates which form the partition walls 31 are mounted so that they may be built in after the oven roof and walls are completed and so that they may be removed and replaced if desired. As shown in Fig. 2, the roof arch which is of refractory material 15 like the walls 30, has projecting bricks 35 between which are held the upper ends of the plates forming the partition walls 31. These bricks are preferably made of some strong refractory material such as carbo- 20 rundum. The lower ends of the wall plates are set into recessed bricks 36. In putting in the walls, the wall plates are fitted between the roof bricks 35 and the recessed bricks 36 are brought up to inclose the lower ends of 25 the wall plates. Then ordinary rectangular bricks 37 are thrust beneath the recessed bricks 36 to support them and to hold the wall plates locked in position.

The oven chamber 2 has no central partition as in some types of double tunnel ovens. A central pier 40 extends along between the trucks but above this pier the oven is open from side to side. At the extreme ends of 30 the oven, shields 41 are provided to screen the incoming goods from a too quick heating by the heated outgoing goods. As shown in Fig. 1, these heat screens extend like wing walls a short distance into the tunnel chamber from each end and are formed of sheets 35 of corrugated metal. These shields prevent direct exchange between the outgoing goods and the incoming goods and thereby prevent the incoming goods from receiving a too quick shock of heat. When the heat shields 40 are formed of metal, as shown in Fig. 1, preferably no openings are provided through the metal so that the heat exchange between the heated outgoing goods and incoming goods takes place by the outgoing goods heating 45 the metal wall 41 by convection currents between the wall and the outgoing goods. This induces convection currents between the heated shield and the incoming goods to cause a gradual heating thereof.

In Fig. 4 is illustrated a modification of the heat shields. As shown in Fig. 4, the heat shield is built up of a plurality of overlapping piers 42 having tortuous air openings between them. When this type of wall 50 is used the incoming goods are shielded against direct heat radiations from the outgoing goods but a convection circulation of heated air is formed through the tortuous and restricted openings 43.

65 As will be readily understood by those

skilled in this art from the foregoing description, the articles to be fired or heat treated are placed upon the trucks which are introduced into the oven chamber through the vestibules 11. These trucks are pushed 70 through the oven chamber in opposite directions as indicated by the arrows *h* in Fig. 1. As the goods travel through the oven, they are first heated by the heat from the combustion of the fuel and also from the heat 75 given up by the outgoing oppositely moving goods. The goods, as first introduced into the oven, receive heat through the wall 31 on the one side, and from the heated outgoing goods on the other side. This heat is 80 tempered by the heat shield 41. The heat which the goods receive from the combustion of the fuel at this point is a comparatively gentle heat through the metal wall 33 which is at the cooler end of the heating 85 flue 23. As the goods pass beyond the end of the heat shield 41, they come into the more highly heated portion of the chamber in which they are subjected to the direct heat from the outgoing goods on the one side 90 and from the more highly heated refractory walls of the heating flue on the other side. The goods travel along until they reach the zone of maximum heat, which is between the two combustion chambers 22. Thereafter 95 they travel along opposite the wall of the furnace which has no heating flues. Here the goods are gradually cooled, giving up their heat to the oppositely moving lines of cool incoming goods. The goods are then 100 pushed out of the furnace into the antechamber 11 where the gradual cooling of the goods may be completed if desired, before they are taken into the outer air.

This furnace structure allows a proper 105 distribution and regulation of the heat. In the heat treatment of certain articles it is desirable that the heat treatment follow a certain definite cycle. For example, in firing certain ceramic goods it is desirable that 110 the goods be first heated to slightly above the boiling point of water and then kept at this temperature for a substantial length of time, until the free water is evaporated. After the water is driven off the temperature 115 of the goods can be increased relatively rapidly until the temperature of dehydration or calcining is reached. Then the temperature should be held approximately constant until the water of crystallization is 120 driven off. Then the goods may be again heated comparatively rapidly until the temperature of fusion of the bond or flux is reached. The goods should then be held at substantially this temperature for a considerable length of time until the firing is 125 completed. After this the temperature of the goods should be gradually reduced. For the most economical and rapid operation of an oven, the times between the neces- 130

sary periods of substantially constant temperature should be made as short as possible. For example, while the three periods of free water evaporation, dehydration, and fluxing should consume substantial amounts of time, the transition periods may be comparatively short. In other words, the gradient of the curve representing the relation between the temperature and the time should be small at some portions of the curve and comparatively large at others. The desired time-temperature relation is obtained in the old style intermittent bee-hive oven by varying the rate of combustion to approximate the desired time-temperature cycle. In continuous ovens the rate of combustion of the fuel must be maintained substantially uniform. In the usual type of continuous ovens, the temperature is gradually increased so that the rise in temperature will not be too rapid during the periods which require an approximately constant temperature. The temperature-time curve has had a small and substantially constant gradient throughout. While such heating does not damage the goods, it consumes an unnecessary amount of time during the transition periods. In my oven, I maintain a substantially constant combustion of the fuel and at the same time get the desired quicker temperature cycle having the necessary periods of approximately constant temperature and transition periods of quicker temperature increase. I maintain such heat distribution in the oven chamber that the goods pass through zones of approximately constant temperature and intervening zones of more rapidly increasing temperature.

In Figs. 5, 6 and 7 I have illustrated three ways of a possibly greater number, of controlling the heat distribution to maintain the heating zone when a flue is utilized in which combustion takes place at one end and the products of combustion travel longitudinally along the flue with gradually decreasing temperature. It is to be understood, however, that the invention is not limited to this type of flue, or to the illustrated construction for establishing the heat zones, as they are intended to be merely illustrative.

In Figs. 5, 6 and 7, the same heating flue as shown in Fig. 1 is illustrated. This flue 20, as in Fig. 1, has the combustion chamber 22 and the long flue proper 23 between the combustion chamber and the chimney flue 24. The greatest heat is, of course, at the point of combustion along the wall opposite the chamber 22. The heat of the gases gradually diminishes along the long flue 23. In these figures, I have illustrated an arrangement whereby the goods travel through four zones indicated by reference characters A, B, C and D. A represents a zone along which the temperature increases

comparatively rapidly. B represents a zone along which the temperature is approximately constant. C represents a second zone of increasing temperature. D represents a second approximately constant temperature zone. Four zones are shown for the purposes of illustration. In actual practice there may be a greater number of zones and they may be differently arranged depending upon the character of the materials to be treated.

Referring first to Fig. 5: The heat distribution is obtained by varying the thickness of the conducting partition wall 31. As shown in this figure, the partition wall comprises a metal plate extending from *a* to *b*, a comparatively thin carborundum plate extending from *b* to *b'*; a thicker carborundum plate extending from *b'* to *d*; a thicker carborundum plate extending from *d* to *d'*, and a still thicker carborundum plate extending from *d'* to *d''*. It will be seen, therefore, that the heating chamber or flue 20 has a partition wall decreasing in thickness but in a definite manner.

It is desired to have the zone D, a zone of approximately uniform temperature. Therefore, opposite the combustion chamber 22 is placed the thickest carborundum plate. Where the gases have cooled somewhat, as between *d'* and *d*, a thinner plate is put, and where the gases have cooled still more, as between *d* and *b'*, a still thinner plate is used. The heat can pass more readily through the thinner plates so that by making the plates of proper thickness and relative length, the heat transfer between the heating flue and the oven chamber may be made substantially uniform along the zone D. It will be noted that the portion of wall between *d* and *b'* is made comparatively long and of uniform thickness. This gives a zone C along which the heat transfer varies in accordance with the decrease in temperature of the flue gases. The zone B is formed by the thicker plate at one end, the thin plate at the middle, and the still thinner and better heat conducting metallic plate at the other end so that a substantially constant temperature is maintained in the oven chamber along this zone. The zone A in which the temperature of the goods is increased, is formed by a wall of uniform thickness.

As shown in Fig. 6, similar heating zones are established by varying the corrugations of the partition wall. The greater the corrugation, the greater the heat transfer through the wall.

In Fig. 7 similar heating zones are established by constricting the area of the flue 23. These constrictions are indicated at 50 and 51. The heat exchange between a surface and the gases passing over the surface is dependent, among other things, upon the ve-

locity of the gases passing over the surface, increasing rapidly with increase of such velocity. Therefore, the walls opposite the constrictions 50 and 51 will absorb more heat from the gases than would be the case if the constrictions were not present. In this way the right hand end of the heating zone D may have its temperature maintained substantially as great as the temperature opposite the combustion chamber at which the gases do not travel as rapidly over the surface of the wall 31. The illustrations in Figs. 5, 6 and 7 are intended to be merely schematic and are therefore exaggerated, no attempt being made to get exact proportions. The heat cycle for any particular furnace may be worked out and the heat distribution arranged to give the proper heating zones.

20 The term "constant temperature zone" is intended as a term of general description and not of limitation, and is intended to define those zones in which the variation of temperature is comparatively small as compared with the transition zones of marked temperature increase, and is intended to include zones in which there may be some increase of heat provided such increase is not great enough to damage the goods during 25 the period in question, as for example, the evaporating, calcining, or fluxing periods of baking ceramics.

30 While I have illustrated and described the preferred embodiment of my invention, it is to be understood that the invention is not limited to its illustrated embodiment but may be otherwise embodied within the scope of the invention as defined in the following claims.

40 I claim:

1. An oven comprising a comparatively long heating chamber through which travel the articles to be heated and means for maintaining along the heating chamber zones of approximately uniform temperature separated by zones of changing temperature, substantially as described.

2. An oven comprising a comparatively long heating chamber through which travel the articles to be heated and means for maintaining along the heating chamber zones of comparatively little temperature change separated by zones of comparatively rapid temperature change, substantially as described.

3. An oven comprising a comparatively long heating chamber through which travel the articles to be heated, a longitudinal heating flue in the wall of the chamber, and means for maintaining along the oven chamber zones of approximately uniform temperature separated by zones of comparatively rapid changing temperature by varying the rate of heat delivery along the flue, substantially as described.

4. An oven comprising a comparatively long heating chamber through which travel the articles to be heated, a longitudinal heating flue in the wall of the chamber and separated therefrom by a partition wall, and means for varying the relative heat transfer by the wall at predetermined places along the flue so as to establish along the heating chamber zones of comparatively little temperature change separated by zones of comparatively rapid temperature change, substantially as described.

5. An oven comprising a tunnel-like heating chamber having two tracks along which the articles to be heated travel in opposite directions, means for heating the articles, and heat shields at the ends only of the chamber between the lines of incoming and outgoing articles, substantially as described.

6. An oven comprising a comparatively long heating chamber through which the articles to be heated travel in two lines in opposite directions, means for heating the articles and means at the ends only of the chamber for shielding the incoming articles from the heat of the outgoing articles, substantially as described.

7. An oven comprising a comparatively long heating chamber through which the articles to be heated travel in two lines in opposite directions, means for heating the articles, and means at the ends of the chamber for decreasing the heat transfer between the outgoing and incoming articles where their temperature difference is the greatest, substantially as described.

8. An oven comprising a heating chamber and a combustion flue or chamber in the wall of the oven arranged to cause a return or eddy of the gases of combustion, substantially as described.

9. An oven comprising a heating chamber and a burner in the oven wall and a combustion chamber receiving the products of combustion from the burner and arranged to reverse the direction of the stream of the gases of combustion, substantially as described.

10. An oven comprising a heating chamber, a combustion chamber or flue in the wall of the oven, and a corrugated heat conducting partition between the heating chamber and the combustion flue or chamber, substantially as described.

11. An oven comprising a heating chamber, a combustion chamber or flue in the wall of the oven and a generally flat, vertical, corrugated, heat conducting partition between the heating chamber and the combustion chamber or flue, and extending from the top to the base of the heating chamber, substantially as described.

12. An oven comprising a heating chamber, a combustion chamber or flue in the wall of the oven, partition plates between

the heating chamber and combustion chamber or flue, and means for removably holding the plates, substantially as described.

13. An oven comprising a heating chamber, a combustion chamber or flue in the wall of the oven, partition plates between the heating chamber and combustion chamber or flue, means for removably holding the plates comprising locking projections 10 extending from the roof of the oven and a recessed locking means at the bottom of the plates, substantially as described.

14. An oven comprising a heating chamber having a refractory roof, a combustion chamber or flue in the side of the oven, a partition between the heating chamber and combustion chamber or flue comprising a plate of refractory material, and means for holding the partition plate comprising refractory blocks projecting from the roof of the heating chamber and means for holding the bottom of the plate, substantially as described.

15. An oven comprising a heating chamber having a refractory roof, a combustion chamber or flue in the side of the oven, a partition between the heating chamber and combustion chamber or flue comprising a plate of refractory material, means for holding the partition plate comprising refractory blocks projecting from the roof of the oven chamber and means for holding the bottom of the plate including a recessed block fitting around the lower end of the 30 plate and blocks slipped in beneath the recessed block to support it, substantially as described.

16. An oven comprising a comparatively

long heating chamber through which the articles to be heated travel in opposite directions, means for maintaining along the heating chamber zones of comparatively little temperature change separated by zones of comparatively rapid temperature change and heat shields at the ends only of the 45 chamber between the lines of incoming and outgoing articles, substantially as described.

17. An oven comprising a comparatively long heating chamber through which the articles to be heated travel in two lines in 50 opposite directions, means for heating the articles, and substantially unbroken heat conducting shields at the ends only of the chamber between the lines of incoming and outgoing articles, substantially as described.

18. An oven comprising a comparatively long heating chamber through which the articles to be heated travel in two lines in opposite directions, means for heating the articles, and metal heat shields at the ends of 60 the chamber between the lines of incoming and outgoing articles, substantially as described.

19. An oven comprising a comparatively long heating chamber through which the articles to be heated travel in two lines in opposite directions, means for heating the articles, and heat shields at the ends of the chamber between the lines of the incoming and outgoing articles having tortuous heat 70 conducting passages therethrough, substantially as described.

In testimony whereof, I have hereunto set my hand.

SAMUEL TROOD.
